STOKER APPARATUS FOR BROODER HEATERS

Hugh E. Mitchell, Slate Spring, Miss.

Application October 25, 1941, Serial No. 416,560

2 Claims. (Cl. 110—101)

My invention relates to improvements in stoker apparatus for loading fuel into brooder heaters, the principal object in view being to provide a simply constructed apparatus of the character indicated which is automatically operative under the influence of gravity and under control of the heater to deliver into the latter uniform loads of fuel as required.

Other objects are to provide apparatus of the character and for the purpose above set forth which is easy to install, requires a minimum of servicing, and is inexpensive to manufacture.

To the accomplishment of the above, and subordinate objects presently appearing, a preferred embodiment of my invention has been illustrated in the accompanying drawings, set forth in detail in the succeeding description, and defined in the claims appended hereto.

In said drawings:

Figure 1 is a view in side elevation of a preferred embodiment of my improved apparatus.

Figure 2 is a fragmentary view in perspective of the heater grate trip lever.

Figure 3 is a fragmentary view in top plan of the delivery end of the apparatus drawn to an enlarged scale.

Figure 4 is a view in longitudinal section taken on the line 4—4 of Figure 3.

Figure 5 is a fragmentary view of the conveyor track frame together with the trip mechanism and heater opening mechanism.

Figure 6 is a detail fragmentary view of the trip lever and rod, and

Figure 7 is a detail view in side elevation illustrating one of the fuel buckets.

Referring to the drawings by numerals, according to my invention, a box-type, coal or wood burning, brooder heater 1, substantially rectangular, and having a back flue pipe 2 is equipped with a top 3 hinged, as at 4, at its rear side to one side of the body 5 of the heater 1 to open upwardly toward said one side of said body, and said top 3 is counterbalanced for easy opening by an arm 6 extending laterally therefrom and a counterweight 7 suitably secured to said arm.

The heater grate 8 is hinged at one side thereof, as at 9, to one side of the body 5 for vertical swinging movement, for a purpose presently described, and is overbalanced to swing upwardly and through the medium of an overbalance weight 10 suitably mounted on the same side of said body 5 as the weight 7, and on one end of the lever 11 pivoted, as at 12, adjacent its other end for vertical swinging movement on an angle

bracket 13 fixed on the body 5, said other end of the lever 11 being operatively connected to the grate 8 by a link 14 pivoted, as at 15, to said lever 11 and also pivoted, as at 16, to an angle arm 17 depending from the free edge of the grate 8 and extending out of a slot 18 provided in the body 5 below said grate 8.

The above-described overbalance mechanism for the grate 8 is designed to be overcome so as to permit the grate to assume horizontal position under a maximum weight of fuel deposited on said grate.

At the same side of the heater 1 as the front side of the top 3 is an elongated, substantially horizontally disposed conveyor frame 19 extending lengthwise laterally of the adjacent side of the heater body 5 and suitably located above the level of the top 3. The basic elements of the frame 19 are a pair of substantially horseshoe-shaped, side members of angle iron opposed to each other to form upper and lower tracks 20, 21 with ends terminating adjacent the heater 1. The upper tracks incline downwardly toward the heater 1 and include end sections 22 inclining at a greater angle than the remainder of the tracks. The lower tracks 21, in each instance, include a horizontal section 23 downwardly offset from the rear portion of the track and attached at one end to the rear portion by a hanger 24 so as to provide a gap between the section 23 and rear portion to permit conveyor rollers, presently described, to ride off the section 23 around the curve of the member and onto the upper track 20. The ends of the upper tracks 20, and the corresponding ends of the sections 23 are supported by brackets 25 suitably secured thereto and to the side of the heater 1. Legs, as at 25', support the frame members 19 at a suitable distance from the brackets 25.

The described conveyor frame 19 supports a pair of link conveyor side chains 26 the links of which are pivotally mounted on cross-shafts 27 equipped on the ends thereof with rollers 28 adapted to ride on the described tracks 20, 21. A pair of disc-like idler pulleys 29 are rotatably mounted between the tracks 20 adjacent the ends of the latter upon a cross-shaft 30 suitably mounted in bearing brackets, as at 31, depending from said tracks 20, said pulleys 29 supporting the conveyor chains 26 at what constitutes the front or delivery end of the conveyor. As will be understood, the links of the conveyor chains 26 are opposed in pairs at opposite sides of the frame 19 to form top and bottom stretches of said chain,

and the top stretches of said chains are designed to travel toward the heater 1.

Fuel buckets are carried by the cross-shafts 27. Each bucket comprises an open sided frame 33 having end walls 34 and a bottom 35 fixed at one end thereof on corresponding ends of a pair of cross-blocks 36 journaled on a cross-shaft 27 in front of the bucket 26 so that the frames on the top stretch of the conveyor pivot on a preceding cross-shaft 27 and at their rear ends seat on the cross-blocks of a trailing cross-shaft 27, whereby, as said frames 33 travel around the pulleys 29 they swing downwardly and forwardly into inverted dumping position. As best shown in Figures 1 and 4, in the dumping positions of said frames 33 the buckets empty into the body 5 of the heater 1 and then travel away from said heater clear of the same and in inverted position. Suitable stop means may be utilized to establish the dumping position of the frames 33. Suitably fixed in each bucket frame 33 for removal therefrom is a receptacle section 37 for containing coal, the section fitting in the frame and being preferably anchored thereto by a bottom stud 38 extending through the bottom 35 of the frame 33 and equipped with a nut. The frames 33 are designed for holding stick wood when the sections 37 are removed.

At this point, it may be explained that by virtue of the inclined tracks 20, under the weight of the loaded frames 33, or sections 37 of the described buckets on the top stretches of the conveyor chains 26, said chains are caused to roll down the inclined tracks 20 to the delivery end of the conveyor and to dump in the manner already described.

The described conveyor is held stationary by a grate operated trip mechanism as follows:

A trip lever 39 fixed to the hinged side of the grate 8 extends laterally out of the body 5 of heater 1 alongside one side of the conveyor frame 19, said lever having an inner end suitably fixed to said grate 8. The outer end of the lever 39 is adapted to be connected in a manner presently described to the lower end of an upright trip rod 41, the upper end of which rod is pivoted, as at 42, to the pivotal connection of a pair of toggle links 43 one of which has one end pivoted, as at 44, to one track 20 and the other of which has one end pivoted, as at 45, to an upright crank arm 46 fast on one end of a trip rock shaft 47 extending transversely of the tracks 20 and suitably journaled in bearings, as at 48, on the under face of said tracks. A pair of upstanding trip arms 49 are fixed on said shaft 47 to extend upwardly between the tracks 20 into the path of travel of the roller cross-shafts 27. A trip lug 50 on the trip lever 39 is provided to hook over a stop lug 51 on the lower end of the trip rod 41, and a forked guide plate 52 on said trip lever 39 straddles the trip 41 all for a purpose presently seen. A coil spring 53 suitably connected at its ends to the trip rod 41 and to one of the tracks 20 urges said rod 41 upwardly and its lower end toward the trip lug 50.

Referring to the operation of the parts as so far described, with a maximum load of fuel on the grate 8, the latter is depressed thereby into substantially horizontal position and the trip lever 39 extends substantially horizontally therefrom. The spring 53 pulls the lower end of the trip rod 41 toward the trip lug 50 and the latter hooks over the stop lug 51 and blocks upward movement of the trip rod 41. In this blocked, or locked, position of the trip rod 41 the toggle

links 43 are held horizontally aligned, the trip arms 49 project upwardly in front of one roller carrying shaft 27, and rocking of said trip rock shaft 47 is blocked by a dead center relation of the pivots 44, 42 and 45 opposing movement of the crank arm 46. When the fuel on the grate 8 has burned out to an extent such that the weight on the grate 8 is reduced to a degree permitting said grate to be overbalanced by the described overbalancing mechanism therefor, said grate 8 is swung upwardly by said overbalancing mechanism with the result that the trip lever 39 is swung downwardly thereby pulling the trip rod 41 down through engagement of the trip lug 50 with the stop lug 51, whereby the toggle formed by the links 43 is broken at the pivotal connection 42 of said links. Such operation of the toggle pulls the crank arm 46 to rock the trip rock shaft 47 in the proper direction to swing the trip arms 49 in the direction of travel of the upper stretch of the conveyor chains 26, thereby removing said arms 49 from blocking relation to the roller carrying shaft 27 thus releasing the described conveyor for gravitational operation to move a leading fuel bucket into a position to dump in the manner already described in the foregoing. As soon as the grate 8 is again loaded, by dumping of said leading bucket, it will assume horizontal position, also the trip lever 39 will assume a corresponding position.

As each fuel bucket moves toward dumping position it operates means for opening the heater top 3, said means comprising a crank arm 54 fast on the rock shaft 55 journaled in bearings 56 on the tracks 20 to extend across the latter. A pair of depending crank arms 57 are fast on said shaft 55 and pivotally connected, as at 58, to one end of a pair of rods 59 having their other ends pivotally connected, as at 60, to arms 61 suitably connected to the heater top 3. A coil spring 62 attached to the rock shaft 47 and to the crank arm 54 normally swings the latter into upright position in which it is interposed directly in front of the roller carrying rod 27 located in front of the one blocked by the trip arms 49.

The operation of the described top opening means is as follows: The roller carrying shaft 27 preceding each fuel bucket traveling into dumping position wipes over the crank arm 54 and swings the same in the direction of travel of the bucket to rock shaft 55 in opposition to the spring 62 and swings crank arms 57 in a direction to exert a pulling action on the rods 59 which by virtue of connections 60, 61 to top 3 opens the latter just prior to dumping of a preceding full fuel bucket. As soon as one bucket dumps, the crank arm 54 is released so that the parts of the top opening means are returned to normal position by the spring 62, and the top 3 closes.

Means are provided for disabling the described trip mechanism when the top 3 is opened, to thereby prevent a double load from being dumped into the heater 1. This means comprises a bell crank 63 pivoted, as at 64, on one track 20 intermediate one crank arm 57 and the trip rod 41, and a cam 65 fast on rock shaft 55, the arrangement being such that when crank arm 57 is swung, as previously described, to effect opening of the top 3, said cam 65 moves one end of the bell crank 63 and swings the other end of said crank against the trip rod 41 to swing the latter on its pivot 42 in opposition to the spring 53 so that the lower end of the trip rod 41 is caused to move the stop lug 51 from under the trip lug 50 whereby the trip rod 39 is rendered ineffective.

to operate said trip rod. As soon as the top 3 is closed, the cam 65 releases the bell crank 63 and the latter releases the trip rod 41, whereupon the spring 53 acts to swing the trip rod 41 to relocate the stop lug 51 beneath the trip lug 50 and render the trip lever 39 effective to operate the trip rod 41, as will be clear.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the subjoined claims.

Having thus described my invention, what is claimed as new is—

1. The combination with an open top heater, of a counterbalanced fuel supporting grate therein vertically movable under decrease in weight of a load therein in predetermined degree, means to

feed fuel into the top of said heater operative intermittently under the influence of gravity, means to control operation of said fuel feeding means operative by vertical movement of said grate, a normally closed hinged top for said heater, and means to open said top operative by said fuel feeding means.

2. The combination with an open top heater, of a counterbalanced fuel supporting grate therein vertically movable under decrease in weight of a load therein in predetermined degree, means to feed fuel into the top of said heater operative intermittently under the influence of gravity, means to control operation of said fuel feeding means operative by vertical movement of said grate, a normally closed hinged top for said heater, means to open said top operative by said fuel feeding means, and means to disable said control means operative by said top opening means.

HUGH E. MITCHELL.
